FOLDING MITER GAUGE

Reland J. Colton, Port Washington, N. Y.

Application May 16, 1946, Serial No. 670,225

3 Claims. (Cl. 33—91)

1

My invention relates to geometrical instruments and has as its object the provision of a simple folding miter gage which folds into a compact form when not in use, and is inexpensive to manufacture.

The embodiment of my invention comprises an inverted V type angle bisector having V hinged regulating arms wherein there is no vertical central bar used to maintain the apex of the V equidistant in relation to the sides of the inverted V elements.

The appended specification and drawings will enable those versed in the arts to which my invention pertains to make and use this device.

Referring to the drawings; Figure 1 is a fragmentary plan view of my invention showing the arms of the inverted V at 1 and 5 with the regulating arms of the V shown at 9 and 10, with the outer circumference of guide discs shown at 2 and 15. The arms of the inverted V are capable of arcuate movement on the hinge pin shown at 3, while the regulating arms 9 and 10 are hinged on the pins 14, 7 and 8. The surfaces indicated at 1, 3, 5, 7, 8, 9, 10 and 14 are all on the same plane. An angle is formed on the arms of the inverted V as indicated by the lines 11 and 12 to enable the user to use this device as a template for the angular measurement of internal or external corners as when affixing moulding to the inside of a room ceiling or the outside of a shelf where the angle is unknown.

In using this device, it is not necessary for the user to know the number of degrees in the angles involved. Merely setting the inverted V to correspond with the lines of the object where it is desired to affix moulding or other such material will align the guide discs 2 and 15 so that when placed against the side of the said moulding, the miter line will correspond with the outside of whichever arm of the inverted V is in contact with the aforesaid moulding. This is shown where a piece of moulding 18 is in contact with the guide discs as indicated at 19 and 21 with the miter line parallel with the line 13. The moulding 18 would then be cut and placed parallel with the line 11. Means of locking the regulator arms in a fixed position is provided by a knurled head set screw at the back of the guide disc 15. The regulator arms of the V may be identical with their upper ends made narrow, as indicated at 20 to allow the use of a mortice hinge in the elements 1 and 5.

Figure 2 is a fragmental plan view of my invention in the folded position and showing a milled slot at 6 which receives the thin part of the

2

regulator arm 10 when the inverted V is changed to a straight line.

Figure 3 is a perspective fragmental view of parts of the regulator arms 9 and 10 with the pin 14 firmly affixed to the arm 9 by any well known means such as a keyway and key, tapered pin or brazing, and the lower end of the said pin is drilled and tapped to receive the set screw 17. The guide disc 15 forms a cylinder of sufficient depth to encompass part of the pin 14 with sufficient clearance between the lower end of the pin 14 and the bottom of the said cylinder to allow the said screw 17 to firmly press the element 10 between the elements 9 and 15 when 15 the knurled knob 16 is turned to cause the aforesaid screw 17 to be screwed into the pin 14.

Without departing from the scope of my invention, the cylinder formed within the element 15 may have an internal thread and the pin 14 20 may have an external thread to enable the user to lock the regulator arms by screwing the element 15 further on to the pin 14 while the screw 17 would be omitted. In Fig. 1 the method of attaching the pin 3 to the guide disc 2 may be 25 any of the well known methods such as a press fit, riveted, screwed or brazed, or the said pin 3 may be integral with the said guide disc 2. The angle section of the inverted V may also be omitted, and various scales may be inscribed on 30 the arms for special work.

Obviously there must be no lost motion in the various hinges of this device, and offset hinges are preferred, as indicated by the difference in 35 the opposite sides, as indicated in Fig. 2 at 4. The materials used in the construction of this device may be any materials found suitable.

Having described my invention, I claim:

1. In a folding miter gage, shaft means, a pair 40 of arms having their outer ends pivotally connected together by said shaft means, a second shaft means, a second pair of arms having corresponding ends thereof pivotally connected together by said second shaft means, pivotal connections between the other ends of said last pair 45 and the arms of the first pair intermediate said ends, thereby forming a parallelogram, a gage disc secured to and depending from said first shaft means, a second gage disc secured to and depending from said second shaft means and 50 consequently dirigible with respect to said first gage disc, whereby as said arms are moved apart said second gage disc is moved toward said first gage disc and as said arms are moved toward each other said second disc is caused to move in a direction away from the first disc, said movement 55

being along a line bisecting the angle formed by said arms, and clamping means for positively clamping said gage after it has been set.

2. In a folding miter gage, shaft means, a pair of arms of generally L-shaped cross-section and having their horizontal portions at the outer ends pivotally connected together by said shaft means, the vertical edges of said arms constituting ruling or engaging edges, a second shaft means, a second pair of arms having corresponding ends thereof pivotally connected together by said second shaft means, said last arms being generally rectangular in cross-section, pivotal connections between the other ends of the arms of said second pair and the arms of said first pair intermediate the ends thereof to form a parallelogram, an engaging disc secured to and depending from said first shaft means, a second engaging disc secured to and depending from said second shaft means, said second disc consequently being dirigible with respect to said first disc, whereby the movement of said arms apart causes said second disc to move toward said first disc along a line bisecting the angle formed by said arms and movement of the arms toward each other causes said second disc to move along said line in the opposite direction, and clamping means for positively clamping said gage after it has been set.

3. In a folding miter gage, shaft means, a pair of arms generally L-shaped in cross-section and having their horizontal webs at the outer ends thereof mortised and pivotally connected together by said shaft means, the surfaces of said webs lying on a common plane, a second shaft means, a second pair of arms having corresponding ends thereof mortised and pivotally connected together by said second shaft means, whereby the surfaces

of said second pair of arms lie on a common plane, pivotal connections between the other ends of the arms of said second pair and the arms of said first pair intermediate the ends thereof to form a parallelogram, an engaging disc secured to said first shaft means and positioned below and substantially in contact with the lower surfaces of said arms where they are pivotally connected by said first shaft means, a second engaging disc secured to said second shaft means and positioned below and substantially in contact with the lower surfaces of said second pair of arms where they are pivotally connected together by said second shaft means, whereby said second disc is dirigible with respect to the first disc and movement of said first pair of arms toward or away from each other causes said second disc to move, respectively, toward or away from said first disc along a line bisecting the angle formed by said first pair of arms, and clamping means carried by said second shaft means for positively clamping said gage after it has been set.
